UNITED STATES PATENT OFFICE.

PETER D. YANKOFF, OF FORT SMITH, ARKANSAS.

SADIRON.

Application filed November 25, 1922. Serial No. 603,216.

To all whom it may concern:

Be it known that I, PETER D. YANKOFF, a subject of the King of Bulgaria, residing at Fort Smith, in the county of Sebastian and 5 State of Arkansas, have invented a new and useful Sadiron, of which the following is a specification.

This invention relates to sad irons and has for its primary object to provide a novel 10 lamp support to be mounted on the iron and placed in circuit with the electric energy passing through the iron, indicating when the energy to the iron has been cut off.

Another object of the invention is to provide 15 an attachment which may be readily and easily applied to the usual electric iron now in use, eliminating the necessity of making alterations in the construction of the iron to accomplish the positioning of the 20 device.

A still further object of the invention is the provision of means to permit the attachment to be applied to irons of various sizes, suitable adjusting means for accom- 25 plishing this result, being provided.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without 35 departing from the spirit of the invention.

Referring to the drawing:

Figure 1 is a side elevational view of an iron supplied with the attachment.

Figure 2 is a fragmental elevational 40 view disclosing the manner of securing the light support.

Figure 3 is a sectional view taken on line 3—3 of Figure 1.

Referring to the drawing in detail, the 45 reference character 5 designates the body portion of the sad iron which is supplied with electric heating elements not shown, which are in circuit with a suitable source of electric supply and through the wires 6.

50 The reference character 7 indicates the

supporting arms that support the handle 8, by means of which the iron is operated. As shown, these arms taper towards their upper ends so that the socket supporting member 9, that is formed with hook members 10 may embrace portions of the arm and create a wedging action between the arm supporting the same and the socket supporting member 9 to secure the socket supporting member in position. 55

This socket supporting member is formed with a circular portion 11 to accommodate the lamp socket 12 in which the bulb 13 is positioned.

A guard 14 forms a part of the socket 60 supporting member and overlies the bulb to protect the hand of the operator from the heat of the bulb.

It is to be understood that the wires leading to the lamp 13 are in circuit with the 70 wires 6 so that when the electric energy has been turned on to the iron, the lamp will be lighted.

Thus it will be seen that when the electric energy has been turned on to cause the heating elements of the iron to be heated, the lamp 13 will be lighted, to the end that the operator may determine at a glance, whether or not the electric current is turned on, thereby eliminating any possibility of the person 75 leaving the iron while the same is in circuit with its source of electric supply. 80

What is claimed as new is:—

In combination with the inclined edges of the supporting arms of a sad iron handle, a 85 supporting member including a circular lamp receiving portion, hook members extending laterally from the circular lamp receiving portion, and adapted to grip the side edges of an arm of the handle support, 90 and an upwardly and downwardly curved guard section formed integral with the circular portion and adapted to lie in close proximity to a lamp positioned in the circular receiving section. 95

In testimony that I claim the foregoing as my own, I have hereto affixed my signature.

PETER D. YANKOFF.
